ABSTRACT OF THE DISCLOSURE

Hydrocarbons containing the carbon atom nucleus of 1,1-di-lower-alkyl-1,2,3,4-tetrahydronaphthalene and dissolved in an aromatic or aliphatic solvent are converted in the presence of $\text{HF}-\text{BF}_3$ to hydrocarbons containing an indene nucleus. For example, 1,1,4,4,5,5,8,8-octamethyl-1,2,3,4,5,6,7,8-octahydroanthracene is converted to 1-isopropyl-3,3-dimethylindene. Although the product always contains an indene nucleus, the specific product depends upon the type of solvent employed.

This invention relates to the rearrangement of certain types of polycyclic hydrocarbons containing a 1,2,3,4-tetrahydronaphthalene nucleus to polycyclic hydrocarbons containing an indene nucleus. For example, 1,1,4,4,5,5,8,8-octamethyl-1,2,3,4,5,6,7,8-octahydroanthracene (herein OMOHA) and 1,1,4,4-tetramethyl-1,2,3,4,5,6,7,8-octahydroanthracene (herein TMOHA) are converted to 1-isopropyl-3,3-dimethylindene (herein I) and 1-isopropyl-3,3,5,5,8,8-hexamethyl-5,6,7,8-tetrahydrobenzindene (herein II) respectively.

I

II

In Canadian Journal of Chemistry, vol. 39, p. 870, 1961, Barclay discloses that OMOHA rearranges in the presence of a solvent and aluminum chloride. If the solvent is tetrachloroethylene or carbon disulfide the product is II whereas if the solvent is benzene the product is 1,1,4,4-tetramethyl-1,2,3,4-tetrahydronaphthalene.

I have now found that in the presence of benzene and using $\text{HF}-\text{BF}_3$ instead of aluminum chloride product I is obtained. In addition, I have found that products I or II can be obtained through the rearrangement of TMOHA in the presence of $\text{HF}-\text{BF}_3$ and a specific type of solvent. If the solvent is an aromatic such as benzene the product is I whereas if the solvent is an aliphatic (preferably saturated) such as heptane the product is II. Analogous reactions take place with analogous starting materials.

2

The starting materials in the invention are polycyclic hydrocarbons containing the carbon atom nucleus of 1,1-di-lower-alkyl-1,2,3,4-tetrahydronaphthalene. This nucleus is the following:

15 where R is a lower alkyl group such as methyl, ethyl, propyl and isopropyl. R normally will not contain more than 4 carbon atoms and is preferably methyl. Examples of compounds containing this nucleus are 1,1-dimethyl 1,2,3,4-tetrahydronaphthalene, 1,1,4,4-tetramethyl, 1,2,3,4-tetrahydronaphthalene, TMOHA, and OMOHA. It will be noted that so long as the specified nucleus is present it 20 may have alkyl groups attached thereto and/or other rings condensed therewith, but any such rings are preferably condensed with the aryl ring of the nucleus. Normally any such alkyl substituents will contain not more than four carbon atoms and preferably are methyl. The 25 preferred starting materials are 1,1-dimethyl-1,2,3,4-tetrahydronaphthalene, 1,1-dimethyloctahydroanthracene and alkyl derivatives thereof, more preferably TMOHA and OMOHA.

30 The products obtained by the rearrangement of the above described starting materials according to the invention contain the indene nucleus which is:

35

40

45 The indene nucleus is formed by contraction of the saturated ring in the 1,1-di-lower alkyl 1,2,3,4-tetrahydronaphthalene nucleus of the starting material. This contraction expels a carbon atom which in combination with the two lower alkyl groups on the starting material forms a single alkyl group in the one position of the indene nucleus. For example,

50 The starting materials are rearranged according to the invention by contacting same with $\text{HF}-\text{BF}_3$ at a temperature of 10–100°C., in the presence of a solvent, and for a time sufficient to effect ring contraction as described above. The amount of HF should be at least 1 mole per mole of starting material and the amount of BF_3 should be at least 0.1 mole per mole of starting ma-

terial. Preferably the mole ratio of HF and BF_3 to starting material is at least 10:1 and 0.5:1 respectively, more preferably at least 50:1 and 1.0:1 respectively. The HF should be employed in liquid phase. Normally the BF_3 pressure in the reaction vessel is sufficient to maintain the HF in liquid phase but if not the vessel can be pressured with nitrogen, etc. in order to achieve this result. The reaction time required to effect ring contraction is normally 1-120 minutes but preferably the reaction time is 10-120 minutes. Preferably the temperature is 20-70°C. and in any event it should be above the freezing point of the solvent.

The type of solvent employed will determine the specific products obtained. For example, with a polyalkyl-octahydroanthracene such as TMOHA and an aromatic solvent such as benzene one ring of the starting material is eliminated and the product is I whereas the use of an aliphatic solvent such as heptane with the same starting material yields II with no ring elimination. Although other solvents can be employed, e.g., hexane, the solvent should be inert by which is meant that it does not interfere with the reaction. The amount of solvent employed should be

5 10 15 20

flushed out with nitrogen and is then evacuated. A 10 weight percent solution of the starting material in solvent is charged to the reactor, the solution is frozen by means of Dry Ice, and the HF is then drawn in. The amount of starting material employed is one gram and is the same in all runs. The BF_3 is then added, the reactor is shaken and is then heated to the desired reaction temperature. In all runs the BF_3 pressure is sufficient to maintain essentially all of the HF in liquid phase. The reactor is then held at the reaction temperature for the desired reaction time. Shaking of the reactor continues throughout the entire reaction time. At the end of the reaction period the reactor is cooled to 15°C., opened, and the contents thereof quenched in ice. Two liquid layers result, an aqueous acid layer and an organic layer. This two-phase system is neutralized with Na_2CO_3 after which the organic layer is drawn off and washed several times with twice its volume of water. The organic layer is then analyzed by vapor phase chromatography and the results are as shown in the Table I below. Analogous results are obtained with other starting materials of the type described and other reaction conditions are specified.

TABLE I

Run	Starting Material	Solvent	Reaction		Catalyst Mole Ratios		Composition of Reaction Product Mixture, wt. percent					
			Temp., °C.	Time, min.	HF to Starting Material	BF_3 to Starting Material	1,2,3,4-tetrahydronaphthalene	1,1,4,4-tetramethyltetralin	Starting Material	I	II	Other
442525	OMOHA	Benzene	30	30	179:1	1.3:1	-----	42.6	17.7	17.3	-----	22.4
442698	TMOHA	do	50	60	245:1	2.5:1	34.9	-----	11.8	16.7	-----	36.6
442699	TMOHA	do	50	60	256:1	16.6:1	40.7	-----	12.5	21.8	-----	25.0
467537-3	TMOHA	Heptane	50	60	130:1	1.8:1	13.6	-----	25.5	-----	33.1	27.8

sufficient to dissolve all the starting material. Normally a 1-50 weight percent solution of starting material in solvent will be used.

The starting materials of the invention can be made by known techniques. See, for example, JACS, vol. 62, pp. 41-43, 1940.

The rearrangements can be carried out in any convenient manner in conventional equipment. For example, a solution of the starting material in the solvent is charged to a closed reaction vessel equipped with heating and agitation means. The reactor is then immersed in a dry ice bath to freeze the starting material solution so that it will not boil when the reactor is subsequently evacuated to draw in the HF. The required amount of HF is then added in the manner described after which the reactor is removed from the ice bath and the desired amount of BF_3 is added. The vessel is then preferably shaken or the contents thereof otherwise agitated in order to insure efficient contact of the HF- BF_3 catalyst with the starting material. After adding the BF_3 the reaction mass is heated to and then maintained at the desired reaction temperature for the desired reaction time. At the end of the reaction period the vessel is opened, which effects removal of most of the BF_3 , and the remaining reaction mass is quenched in ice water. Two liquid layers result, an aqueous acid layer and an organic layer. If desired, the acid in this two-phase system can be neutralized by mixing the system with Na_2CO_3 . The organic layer is then decanted and is preferably washed with water several times to remove any remaining traces of acid or any traces of Na_2CO_3 . The rearrangement product is then separated from the organic layer by conventional means such as distillation or chromatography. Any unreacted starting material can also be recovered by conventional means and can be recycled to the reaction vessel for subsequent rearrangement.

The following examples illustrate the invention more specifically. The procedure in each run is essentially the same and is as follows:

The reaction vessel is a small reactor equipped with a shaker and heating and cooling means. The reactor is

The invention claimed is:

1. Method which comprises contacting a polycyclic hydrocarbon containing the carbon atom nucleus of 1,1-di-lower alkyl-1,2,3,4-tetrahydronaphthalene with liquid HF and BF_3 , said polycyclic hydrocarbon being dissolved in an aromatic or aliphatic solvent therefor, said contacting being at a temperature of 10-100°C., the amount of HF being at least one mole per mole of said polycyclic hydrocarbon and the amount of BF_3 being at least 0.1 mole per mole of said polycyclic hydrocarbon, continuing said contacting for a time sufficient to effect contraction of the six-membered ring of said nucleus to a five-membered ring, thereby to form a polycyclic hydrocarbon product containing the carbon atom nucleus of indene.
2. Method according to claim 1 wherein the temperature is in the range of 20-70°C.
3. Method according to claim 1 wherein said polycyclic hydrocarbon is 1,1,4,4,5,5,8,8-octamethyl-1,2,3,4,5,6,7,8-octahydroanthracene.
4. Method according to claim 1 wherein said polycyclic hydrocarbon is 1,1,4,4-tetramethyl-1,2,3,4,5,6,7,8-octahydroanthracene.
5. Method according to claim 1 wherein said solvent is benzene.
6. Method according to claim 1 wherein said solvent is heptane.
7. Method according to claim 1 wherein said polycyclic hydrocarbon is 1,1,4,5,5,8,8-octamethyl-1,2,3,4,5,6,7,8-octahydroanthracene, said solvent is benzene, said product is 1-isopropyl-3,3-dimethylindene, and the latter is recovered from the reaction product mixture.
8. Method according to claim 1 wherein said polycyclic hydrocarbon is 1,1,4,4-tetramethyl-1,2,3,4,5,6,7,8-octahydroanthracene, said solvent is benzene, said product is 1-isopropyl-3,3-dimethylindene, and the latter is recovered from the reaction product mixture.
9. Method according to claim 1 wherein said polycyclic hydrocarbon is 1,1,4,4-tetramethyl-1,2,3,4,5,6,7,8-octahydroanthracene, said solvent is heptane, said product is 1-isopropyl-3,3,5,5,8,8-hexamethyl-5,6,7,8-tetrahydro-

benzindene and the latter is recovered from the reaction product mixture.

10. Method according to claim 1 wherein the amount of HF is at least 10 moles per mole of said polycyclic hydrocarbon and the amount of BF_3 is at least 0.5 mole per mole of said polycyclic hydrocarbon. 5

11. Method according to claim 1 wherein said polycyclic hydrocarbon is 1,1-dimethyl-1,2,3,4,5,6,7,8-octahydroanthracene or an alkyl derivative thereof.
